(57) **CLAIM**

The ornamental design for a work light, as shown and described.

DESCRIPTION

FIG. 1 is a front view of a work light showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof;

FIG. 9 is a front perspective view thereof, in use;

FIG. 10 is a front perspective view of the work light shown in a second alternate position;

FIG. 11 is a rear perspective view of the work light shown in a second alternate position;

FIG. 12 is a front perspective view of the work light shown in a third alternate position; and,

FIG. 13 is a rear perspective view of the work light shown in a third alternate position.

The broken lines in the drawings illustrate portions of the work light that form no part of the claimed design.
